UNITED STATES PATENT OFFICE.

WILBUR P. RICHARDSON, OF BEAVER, PENNSYLVANIA, ASSIGNOR TO PITTSBURGH EQUIPMENT COMPANY, OF PITTSBURG, PENNSYLVANIA, A CORPORATION OF PENNSYLVANIA.

SIDE-FRAME CONSTRUCTION.

No. 877,735.

Specification of Letters Patent.

Patented Jan. 28, 1908.

Application filed March 27, 1907. Serial No. 364,843.

To all whom it may concern:

Be it known that I, WILBUR P. RICHARDSON, of Beaver, in the county of Beaver and State of Pennsylvania, have invented certain new and useful Improvements in Side-Frame Construction, of which the following is a specification.

This invention relates to improvements in side-frame construction for car-trucks and to this end my invention consists in a new and improved side-frame construction, in the novel features of construction and in the combination of parts all as fully hereinafter described and claimed.

In the accompanying drawing, which illustrates applications of my invention, Figure 1 is a side elevational view of a side-frame construction embodying my invention; Fig. 2 a broken view similar to Fig. 1 showing a modified form of construction; Fig. 3 a part plan and a part sectional view of the form of Fig. 2 taken on line 3—3 of Fig. 2; Fig. 4 a sectional view of the form of Fig. 1, the section being taken on line 4—4 of Fig. 1; Fig. 5 a section on line 5—5 of Fig. 4; Fig. 6 a perspective view of the form of removable bolster-guide employed in the form of Fig. 1; and Fig. 7 the form shown by Fig. 2.

Referring to the drawing, the side-frame proper, as illustrated and as preferred, comprises an integral metallic structure comprising a top-member 1, a bottom-member 2 and a web 3, joining the top and bottom-members.

The web of the side-frame is provided with a bolster-receiving opening comprising an intermediate portion 4, which portion is at least as wide as the bolster 5 measured over its column-guides 6. The bolster-receiving opening is contracted at its top and bottom to form portions of less width than the bolster measured over its column-guides.

Adjacent to the sides of the top contracted portion of the bolster-receiving opening are flanges or fixed bolster-guides 7 and extending downwardly from the enlarged intermediate portion and adjacent to the sides of the lower contracted portion I employ flanges or bolster-guides 8.

9 designates removable bolster-guides which are adapted to be placed within the enlarged portion 4 of the bolster-receiving opening. In the drawing, I have shown two forms of removable bolster-guides, the form of Fig. 6 being adapted to be horizontally in-

serted into the desired operative position and the form of Fig. 7 being adapted to be inserted vertically of the side-frame proper. When the form of Fig. 7 is employed the upper member of the side-frame is provided with an opening 10 and the web formed with a groove 11 to receive the removable guide. By forming the opening 10 in the bottom-member and having the groove 11 in communication therewith, the removable guide 65 may be inserted from the bottom of the side-frame instead of from the top as shown. The form of Fig. 7 is provided with a projecting member 12 adapted to fit into a pocket 13, and with an opening 14 to receive a pin 15. 70 The removable bolster-guide of the form of Fig. 6 is provided with engaging-members 16 which members when the guides are placed in position are adapted to engage a flange adjacent to the enlarged portion of the bolster-receiving opening. As shown, these members 16 are located at the upper end of the guides and engage the upper fixed bolster-guides or flanges 7, but if desired they may be placed at the bottom and engage the lower 80 fixed bolster-guides or flanges 8. When placed at the bottom as just described the apertured projections 17 are located on the upper part of the guides instead of at the bottom as shown by the drawing. When in 85 position the projections 17 extend beyond the sides of the enlarged portion of the bolster-receiving opening and are joined by pins 18.

19 designates the usual spring-plank and 90 20 the springs employed in constructions of this class.

What I claim is:

1. In a truck side-frame construction, the combination with a bolster having column-guides, of a side-frame proper formed with a bolster-receiving opening having an intermediate portion at least as wide as the bolster measured over its column-guides and top and bottom portions of less width than the 100 bolster measured over its column-guides, and removable bolster-guides located in the enlarged intermediate portion of the bolster-receiving opening.

2. In a truck side-frame construction, the combination with a bolster having column-guides, of a side-frame proper formed with a bolster-receiving opening having an intermediate portion at least as wide as the bolster measured over its column-guides, an upper 110

portion of less width than the bolster measured over its column-guides, fixed bolster-guides adjacent to the sides of the contracted upper portion, a lower portion of the bolster-receiving opening of less width than the bolster measured over its column-guides, fixed bolster-guides adjacent to the sides of the contracted lower portion, and removable bolster-guides located in the enlarged intermediate portion of the bolster-receiving opening.

3. In a truck side-frame construction, the combination with a bolster provided with column-guides, a side-frame proper provided with a bolster-receiving opening having an intermediate portion at least as wide as the bolster measured over its column-guides and top and bottom portions of less width than the bolster measured over its column-guides, a removable bolster-guide, said side-frame formed with an opening communicating with the enlarged portion of the bolster-receiving opening to permit the removable bolster-guide to be vertically placed in said enlarged portion.

4. In a truck side-frame construction, the combination with a bolster provided with column-guides, a side-frame proper provided with a bolster-receiving opening having an intermediate portion at least as wide as the bolster measured over its column-guides, and upper and lower portions of less width than the bolster measured over its column-guides, a flange formed on the side frame, and a removable bolster-guide adapted to be placed in the intermediate portion of the opening and provided with an engaging-member adapted to make engagement with the flange.

5. In a truck side-frame construction, the combination with a bolster provided with column-guides, a side-frame proper provided with a bolster-receiving opening having a portion at least as wide as the bolster meas-

ured over its column-guides, engaging means formed on the side-frame adjacent to the widest portion of the bolster-receiving opening, and a removable bolster-guide formed to embrace a portion of the web of the side-frame and having separated engaging-members adapted to make engagement with said engaging means.

6. In a truck side-frame construction, the combination with a bolster provided with column-guides, a side-frame proper provided with a bolster-receiving opening having a portion at least as wide as the bolster measured over its column-guides, a flange formed on the web of the side-frame, and a removable bolster-guide formed to embrace a portion of the web of the side-frame provided at one end with separated engaging-members adapted to make engagement with the said flange and having apertured projections on its opposite end.

7. In a truck side-frame construction, the combination with a bolster having column-guides, of a side-frame proper formed with a bolster-receiving opening having an intermediate portion at least as wide as the bolster measured over its column-guides and top and bottom portions of less width than the bolster measured over its column-guides, engaging-means formed on the side-frame adjacent to the widest portion of the bolster-receiving opening, and a removable bolster-guide formed to embrace a portion of the web of the side-frame and having separated engaging-members adapted to make engagement with said engaging-means.

In testimony whereof I affix my signature in presence of two witnesses.

WILBUR P. RICHARDSON.
